UNITED STATES PATENT OFFICE.

WILLIAM H. SCHOONMAKER, OF MONTCLAIR, NEW JERSEY.

HEATING SYSTEM.

1,418,835.

Specification of Letters Patent. Patented June 6, 1922.

Application filed March 3, 1917. Serial No. 152,198.

To all whom it may concern:

Be it known that I, WILLIAM H. SCHOONMAKER, a citizen of the United States of America, and a resident of Montclair, county 5 of Essex, and State of New Jersey, have invented a certain new and useful Heating System, of which the following is a specification.

My invention relates to improvements in 10 apparatus for house heating and the like, and is applicable to ordinary steam heating systems, either to the so-called "one pipe" or to the so-called "two pipe" systems, also to the modification of steam heating systems 15 known as the vapor heating system. As an apparatus it comprises a suction apparatus connected to the heating coils or radiators of the system, and controlled, automatically, and preferably by the draft damper or 20 damper regulator of the boiler supplying steam to the system, in such manner that when the damper or dampers of the boiler are adjusted to cause increased action of the fire in the boiler the said suction device is 25 started in operation. The construction is also preferably such that when the boiler damper or dampers is or are adjusted to cause decreased action of the fire in the boiler the action of the said suction device 30 is stopped. My invention further comprises means whereby the action of the suction apparatus is stopped upon establishment of a predetermined degree of partial vacuum in the heating system, and is started again upon 35 fall of that partial vacuum below a predetermined degree; and my invention further comprises means whereby upon the establishment of a predetermined temperature in the return or air-withdrawal line of the 40 system, the operation of such suction apparatus is stopped, and is started again upon the fall to a predetermined degree of the temperature in said return or air-withdrawal line. By so applying suction to, or creating 45 a partial vacuum in, the said return or air-withdrawal line, the temperature at which the water in the boiler evaporates is greatly lowered, and thereby the time required to fill the heating coils or radiators with steam 50 is greatly reduced. My invention further comprises means whereby in the event of water being drawn up by suction into the return line of the heating system to some predetermined point, a connection will be 55 opened automatically between the supply

line and return line, balancing pressures, and causing the water drawn up to return to the boiler. Other features of my invention, considered as an apparatus, will be pointed out hereafter.

The objects of my invention are, to render steam heating systems and vapor heating systems more quickly responsive; to cause the heating coils of the radiator or radiators of the system to be filled with steam more 60 quickly, upon the adjustment of the furnace damper or dampers for increased combustion, more particularly when the boiler has not been supplying steam to the heating coils for a considerable length of time (as for example 65 during the night when the boiler has been shut off, i. e., the drafts have been set so that the boiler has not generated steam); to obtain increased fuel economy; and generally to accomplish the above objects while 70 retaining simplicity of apparatus and without material addition to expense of apparatus.

Heretofore so-called "vapor heating systems" have been employed, wherein once 80 steam has been generated in the boiler and heating system, at or above atmospheric pressure, a partial vacuum is maintained, for a considerable time at least, in the heating coils or radiators, and in the boiler; 85 but, these systems, so far as I am aware, have commonly required that steam shall first be generated at or above atmospheric pressure, or else have required that a suction pump shall be started by hand or by means 90 other than the normal automatic control apparatus of the boiler itself. Such apparatus does not provide for the automatic establishment of a partial vacuum in the heating system at the time when that partial vacuum 95 is most needed, i. e., when the drafts of the boiler are opened, automatically or otherwise, in the morning, after the furnace has been shut off all night. It is obvious that if, at or about the time when the drafts of the furnace are opened in the morning, a partial 100 vacuum be applied to the heating coils or radiators of the system, steam will be generated in the boiler much sooner than otherwise, and the heating coils or radiators will 105 be filled with steam much sooner than otherwise.

I will now proceed to describe my invention with reference to the accompanying drawings, illustrating one embodiment of 110

apparatus adapted for carrying out my invention, and will then point out the novel features in claims. In the drawings:

Figure 1 shows, more or less diagrammatically, an elevation of a heating system embodying my invention, installed in a house, the walls and floors of which house are shown in section; Figure 2 shows a central vertical section of an automatic air valve 10 forming a portion of my heating system; Figure 3 shows a central vertical section of a diaphragm-operated valve forming a portion of the control mechanism of an exhauster employed in my said system; Figure 15 4 is a view, similar to Figure 1, showing the application of my invention to a so-called "single pipe" heating system; Figure 5 shows, more or less diagrammatically, an elevation of the said automatic air valve, together with means operated by that air valve 20 for operating a control valve of the said exhauster, such control valve being shown in vertical section; Figure 6 shows a fragmentary vertical section of a float-operated valve 25 employed in my system; and Figure 7 shows a central vertical section of a check valve which may be employed in the single pipe system shown in Figure 4.

Numeral 1 designates an ordinary heating 30 boiler; 2 a steam supply pipe extending therefrom to the radiators or heating coils 3; and 4 designates the return line from the radiators to the boiler. 5 designates the ordinary draft damper of the boiler and 6 35 the ordinary "check" damper in the connection to the smoke pipe 7, these dampers being arranged to be operated automatically by the usual regulating lever 8 itself operated by the usual diaphragm 9, the dampers 40 5 and 6 being connected to lever 8 by the usual flexible connections 10 and 11.

12 designates a valve casing, shown in detail in Figure 2.

13 designates a suction producing apparatus, the particular type of apparatus shown being a water-jet exhauster, of well known construction; though the particular construction of suction apparatus employed is immaterial, in a broad sense. I have 45 shown this suction producing device as provided, in its water supply line, with a valve 14 connected to the regulating lever 8 of the boiler by a connection 15, in such manner that as the damper 5 is opened and the 50 damper 6 closed, the valve 14 will be opened, so starting the suction producing device 13 in operation; and as said damper 5 is closed and damper 6 opened, valve 14 will be closed, so stopping the action of the suction 55 60 producing device 13.

In the water supply line to the exhausting apparatus 13 there is also another valve 16 (see Figure 3) illustrated as of the diaphragm-operated type, and arranged to close when a predetermined degree of suction or

vacuum has been reached in the heating system, and to open when that suction or degree of vacuum decreases considerably; the opening and closing of this valve controlling the action of the exhausting apparatus 13.

Referring now to Figure 2: Within the valve casing 12 there is a thermo-expansible member 17 provided with an adjustable anchoring device 18 at its left hand end. This member 17 is connected by a pivoted lever 19 to a link 20 having a slip-connection with another link 21 itself connected to a check valve 22. Valve casing 12 is interposed in the steam return line 4; and beyond the check valve 22 said valve casing 12 is connected by pipe 23 to the exhauster 13. Furthermore, link 20 is connected to link 21 by a spring-slip-connection 24, which serves to prevent destruction of check valve 22 after valve 22 has seated, in case member 17 expands still further and serves to permit the valve 22 to remain closed upon contraction of member 17. The construction is such that, when there is steam in return pipe 4, such steam will fill the valve casing 12, the varying temperatures of such steam causing varying expansion of the member 17, which expansion is communicated, through lever 19 and links 20 and 21, to valve 22. Should return line 4 be cold, valve 22 will be open. When the steam in the return line reaches some predetermined temperature, the corresponding expansion of member 17 will close check valve 22. The valve casing 12 serves, 95 it will be seen, as a suction-connection between the exhauster 13 and the return line 4.

It may be understood that the regulating lever 8 of the furnace is arranged to be operated by any of the well known devices, (for example, a so-called time-controlled thermostat 25 electrically controlling a damper-operating motor 26) for holding the air draft 5 of the furnace closed and the check valve 6 of the furnace open, during the night, and for opening the air damper 5, and closing the check damper 6, in the morning. Such opening of the air damper and closing of the check damper will be accompanied by a downward motion of the right hand end of lever 8 which will open the valve 14, starting operation of the exhauster 13, and producing a partial vacuum in the heating system, which will insure the filling of that system with steam long before boiling point at atmospheric pressure has been reached in the boiler. When the temperature in the return line 4 has reached some predetermined value, the expansion of member 17 will close valve 22; and almost immediately thereafter valve 120 16 will close, shutting off the exhauster 13; for with valve 22 closed the partial vacuum beyond such valve will quickly reach the value at which the diaphragm actuating device of valve 16 is set to close that valve. 125 130

Preferably, within the valve casing 12 a shield 27, covering the expansible member 17, is provided to prevent direct impact of steam or hot water formed by condensation 5 of the steam upon the member 17. It is intended that this member shall act by expansion due to heat of steam diffused through the valve casing 12, rather than by heat due to impact of steam or hot water directly on member 10 17. Check valve 22 will close (if not already closed) when some predetermined sufficient degree of partial vacuum has been reached in return pipe 4, whether or not the member 17 has expanded to an extent sufficient to close valve 22, the slip connection 15 24 permitting the closing of said valve 22 by partial vacuum derived from pipe 4.

It will be seen that, in the event of lowering of temperature of the fluid returned 20 through pipe 4, below a predetermined degree, expansible member 17 will open valve 22. It will be seen that by this apparatus the radiators 3 are maintained under some suction throughout the day, unless the temperature of the return steam or water becomes so high as to close valve 22, in which event there is no need for partial vacuum in the radiators.

While valve 16, operated by suction, provides a means whereby the operation of the 30 exhauster 13 will be stopped when valve 22 is closed, either by expansion of member 17, or by establishment of a predetermined degree of suction in the return line 4, still it is desirable that means be provided for the 35 stopping of the operation of the exhauster 13 as a result of expansion of member 17 to some predetermined degree, independent of the closing of valve 22, and operation of valve 16. Therefore I have provided mechanical means whereby expansion of member 17 causes the stoppage of the operation 40 of the exhauster. In this way unnecessary intermittent starting and stopping of the 45 operation of the exhauster 13, by valve 16, due to variation of partial vacuum behind the valve 22 when that valve is closed, is avoided.

This mechanical means for controlling the 50 operation of the exhauster 13 by expansible member 17, is shown particularly in Figure 5. In the water supply line 28 leading to the exhauster there is a valve casing within which is a valve 29 adapted to be opened and 55 closed by the raising and lowering of its stem 30. On the pivot shaft 31 of lever 19 (Figure 2) there is an arm 33 having at its end a slot in which works a pin carried by a pivoted arm 34; the other end of this arm 34 60 working between stops 35 and 36 of valve stem 30. A compression spring 37 is arranged to tend to hold arm 34 either in the position shown, or in a reverse position i. e. said spring tends to hold valve 29 either 65 wide open or fully closed. It will be ap-

parent that when member 17, within casing 12, expands sufficiently, arm 33 will have raised arm 34 sufficiently to cause spring 37 to close valve 29 quickly; so stopping the operation of the exhauster 13, and holding 70 that exhauster against operation until, by contraction of member 17, the position of arm 34 is reversed to the position shown in Figure 4; whereupon that exhauster may begin operation again, provided both valves 75 14 and 16 be then opened; and valve 16 will be open, when member 17 is so contracted, unless there be in return line 4 such a predetermined degree of suction that the operation of the exhauster is not required. 80 Whether valve 14 will be opened or not when valve 29 is so opened, will depend upon the position of the damper 5. If damper 5 be closed (for example it may be held closed at the time by the action of the thermostat 85 motor 26) then valve 14 will not be open and exhauster 13 will not operate.

In some conditions it might happen that, through the drawing of a partial vacuum in the return line 4, water might be drawn up 90 into that return line, to a point considerably above the water level in the boiler; and this might lead to very undesirable conditions. To obviate this, I provide, in the return line 4, a float chamber 38, located above the normal water level of the boiler, but below the valve casing 12; and within this float chamber there is a float 39 connected by a rod 40 to a valve 41 having a port 42 adapted, when the float is raised, to place in communication 95 with each other pipe lines 43 and 44 leading respectively to the return line 4 (at a point well above the valve casing 12) and to the supply line 2. It will be seen that water rising in return line 4 to an extent sufficient to 100 partly fill float chamber 38 and to raise the float therein, will result in the connection of pipes 43 and 44, with consequent balancing of pressures (in this case negative pressures) 105 in the two sides 2 and 4 of the heating system; whereupon the water which has risen in the return line 4 will drop again to normal water level.

As illustrated in Figure 4 in the case of a one pipe system, a return pipe 4' may be connected to the ordinary air valves 30' of the radiators 3 and may lead to the valve casing 12, which in that event serves as a supplemental air valve for the entire system, besides serving to regulate the application of 115 vacuum to the radiators and besides serving as means, in connection with the pipe 4', for returning any drip from the air valves to the boiler.

In speaking of partial vacuums, or pressures below atmospheric, it is common to speak of the partial vacuum being increased when the absolute pressure is lowered, and to speak of the partial vacuum as having decreased when the absolute pressure has 125 130

risen. It is in this sense that I have mentioned increase and decrease of suction or partial vacuum in the above description.

What I claim is:

5. 1. In a heating system, the combination of a distributing conduit, means for supplying steam thereto having a damper controlling its operation, means for applying suction to said conduit, and control means for 10 said suction-applying means, comprising means whereby said suction applying means is caused to operate upon change of adjustment of said damper in a sense to cause increase of the heating action of the steam supply means.
15. 2. In a heating system, the combination of a distributing conduit, means for supplying steam thereto having a damper controlling its operation, means for applying suction to 20 said conduit, and control means for said suction-applying means, comprising means for causing said suction applying means to operate upon change of adjustment of said damper in a sense to cause increase of the 25 heating action of the steam supply means and for causing said suction applying means to cease operation upon change of adjustment of said damper in a sense to cause decrease of the heating action of the steam 30 supply means.
3. In a heating system, the combination of a distributing conduit, means for supplying steam thereto comprising a boiler having a damper controlling its operation, 35 means for withdrawing air from said conduit, comprising suction producing means having control means, and operating means for said control means arranged to cause application of suction to said conduit upon 40 adjustment of said damper in a sense to cause increased heating action in said boiler.
4. In a heating system, the combination of a distributing conduit, means for supplying steam thereto comprising a boiler having a damper controlling its operation, 45 means for withdrawing air from said conduit, comprising suction producing means having control means, and operating means for said control means arranged to cause 50 application of suction to said conduit upon adjustment of said damper in a sense to cause increased heating action in said boiler, and arranged to cease application of suction to said conduit upon adjustment of said 55 damper in a sense to cause decreased heating action in said boiler.
5. In a heating system, the combination of a distributing conduit, means for supplying steam thereto comprising a boiler having a damper controlling its operation, 60 means for withdrawing air from said conduit, comprising suction producing means having control means arranged to cause application of suction to said conduit upon 65 adjustment of said damper in a sense to cause increased heating action in said boiler, and arranged to cease application of suction to said conduit upon adjustment of said damper in a sense to cause decreased heating action in said boiler.
70. 6. In a heating system, the combination of a distributing conduit, means for supplying steam thereto comprising a boiler, a valve casing in communication with said distributing conduit, suction producing means, an air withdrawal conduit connected to said casing at one end and to the suction producing means at the other end, a valve within said valve casing, and thermostatic operating means for said valve, located within the casing and arranged to be influenced by the temperature of the fluid in said casing.
80. 7. In a heating system, the combination of a distributing conduit, means for supplying steam thereto comprising a boiler, a suction producing means, a conduit connected at one end with the distributing conduit and at its opposite end with the suction producing means for withdrawing air from the distributing conduit, and control means arranged within the conduit for starting the operation of said suction producing means to cause an increased action of the boiler upon decrease of temperature or for stopping the operation of said suction producing means to reduce the action of the boiler upon increase of temperature in said conduit.
85. 8. In a heating system, the combination of a distributing conduit, means for supplying steam thereto comprising a boiler, suction producing means, an air withdrawal conduit including a casing connected to said distributing conduit at one end and to the suction producing means at its opposite end, and means within the casing for controlling the action of the suction producing means according to the temperature within said casing.
90. 9. In a heating system, the combination of a distributing conduit, means for supplying steam thereto, comprising a boiler having a regulating damper and automatic operating means for said damper, an air withdrawal conduit connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler.
110. 10. In a heating system, the combination of a distributing conduit, means for supplying steam thereto, comprising a boiler having a regulating damper and automatic operating means for said damper, an air withdrawal conduit connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler.
120. 11. In a heating system, the combination of a distributing conduit, means for supplying steam thereto, comprising a boiler having a regulating damper and automatic operating means for said damper, an air withdrawal conduit connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler.
125. 12. In a heating system, the combination of a distributing conduit, means for supplying steam thereto, comprising a boiler having a regulating damper and automatic operating means for said damper, an air withdrawal conduit connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler.
130. 13. In a heating system, the combination of a distributing conduit, means for supplying steam thereto, comprising a boiler having a regulating damper and automatic operating means for said damper, an air withdrawal conduit connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler.

- of a distributing conduit, means for supplying steam thereto comprising a boiler having a regulating damper, and automatic operating means for said damper, an air-withdrawal conduit including a valve casing connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler, and a thermostatic valve arranged within the valve casing and adapted to close the connection between said suction producing means and the distributing conduit upon establishment of a predetermined temperature of the fluid in said valve casing. 10
11. In a heating system, the combination of a distributing conduit, means for supplying steam thereto comprising a boiler having a regulating damper, and automatic operating means for said damper, an air-withdrawal conduit including a valve casing connected to said distributing conduit, suction producing means connected by said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler, a thermostatic valve arranged within the valve casing and adapted to close the connection between said suction producing means and the distributing conduit upon establishment of a predetermined temperature of the fluid in said valve casing. 20
12. In a heating system, the combination of a distributing conduit, means for supplying steam thereto comprising a boiler, having a regulating damper, and automatic operating means for said damper, an air-withdrawal conduit including a valve casing connected to said distributing conduit, suction producing means connected to said air-withdrawal conduit and having control means for starting and stopping the operation of said suction producing means, and means connecting said control means to the automatic damper operating means of the boiler arranged to start the suction producing means in operation when said damper is operated to cause increased action in the boiler, and to stop the operation of said suction producing means when the damper is operated to reduce action in the boiler, a thermostatic valve arranged within the valve casing and adapted to close the connection between said suction producing means and the distributing conduit upon establishment of a predetermined temperature of the fluid in said valve casing. 30
13. In a heating system, the combination with supply and return lines, a boiler connected thereto having a damper controlling its operation, and operating means for said damper, of suction means connected to said return line and arranged to create a partial vacuum therein upon change of adjustment of said damper in a sense to cause increase of action in said boiler. 35
14. In a heating system, the combination of a distributing conduit, means for supplying steam thereto comprising a boiler, suction producing means, an air-withdrawal conduit including a valve casing connected to said distributing conduit, and a valve arranged within the valve casing and having associated therewith a heat-expansible operating means controlled by the temperature of the fluid in said valve casing, of control means for said suction producing means, operated by the expansion of said expansible operating means. 40
15. In a heating system, the combination of a distributing conduit, means for supplying steam thereto comprising a boiler, suction producing means, an air-withdrawal conduit including a valve casing connected to said distributing conduit, a valve arranged within the valve casing and having associated therewith thermostatic operating means controlled by the temperature of the fluid in said valve casing, and control means for said suction producing means operated by said thermostatic operating means. 50
16. In a heating system, the combination of a distributing conduit, means for supplying steam thereto comprising a boiler, suction producing means, an air-withdrawal conduit including a valve casing connected to said distributing conduit, a valve arranged within the valve casing and having associated therewith a thermostatic operating means controlled by the temperature of the fluid in said valve casing, a control valve for said suction producing means, and means operated by said thermostatic operating means and arranged to close and open said control valve. 60
17. In a heating system, the combination of a distributing conduit, means for supply- 65
- means in operation when said damper is operated to cause increased action in the boiler, and to stop the operation of said suction producing means when the damper is operated to reduce action in the boiler, a thermostatic valve arranged within the valve casing and adapted to close the connection between said suction producing means and the distributing conduit upon establishment of a predetermined temperature of the fluid in said valve casing, and means for stopping the operation of said suction producing means upon the closing of said valve and for starting said suction producing means upon the opening of said valve. 70

- ing steam thereto comprising a boiler, said boiler having a controlling damper, suction producing means, an air-withdrawal conduit including a valve casing connected to said distributing conduit, a valve arranged within the valve casing and having associated therewith a thermostatic operating means controlled by the temperature of the fluid in said valve casing, control means 10 for said suction producing means, operated by said thermostatic operating means, means for starting said suction producing means in operation when said damper is adjusted to cause increased action in the boiler and for 15 stopping the operation of said suction producing means when said damper is adjusted to cause decreased action in the boiler, and means for starting said suction producing means in operation upon decrease of partial 20 vacuum in the valve casing to a predetermined degree and for stopping the operation of said suction producing means upon increase of partial vacuum in the valve casing to a predetermined degree.
- 25 18. In a heating system, the combination of a distributing conduit, means for supplying steam thereto comprising a boiler, said boiler having a controlling damper, a suction producing means, an air-withdrawal 30 conduit including a valve casing connected to said distributing conduit, a valve arranged within the valve casing and having associated therewith a thermostatic operating means controlled by the temperature of the fluid in said valve casing, control means 35 for said suction producing means operated by said thermostatic operating means, means for starting said suction producing means in operation when said damper is adjusted to cause increased action in the boiler and for 40 stopping the operation of said suction producing means when said damper is adjusted to cause decreased action in the boiler and an independent means for controlling 45 the actions of said suction producing means in accordance with pressure variations between predetermined limits in the distributing conduit.
19. In a heating system, the combination with a boiler, and the supply and return lines of a heat distributing system connected thereto, of suction producing means connected with said return line and means for

controlling said suction producing automatic means to vary the degree of pressure in the 55 return line inversely with the rise and fall of pressure in the boiler.

20. In a heating system, the combination with a boiler, and the supply and return lines of a heat distributing system connected 60 thereto, of suction producing means connected with said return line, means for controlling the boiler to increase the pressure in the supply line and automatic means for substantially simultaneously controlling the 65 suction-producing means to reduce the pressure in the return line.

21. In a heating system, the combination with a boiler, and the supply and return lines of a heat distributing system connected 70 thereto, of suction producing means connected with said return line, means for controlling the boiler to increase the pressure in the supply line, automatic means for substantially simultaneously controlling the 75 suction producing means to change the pressure in the return line, and independent means for controlling the operation of said suction producing means.

22. In a heating system, the combination 80 of a boiler and the supply and return lines of a heat distributing system connected thereto, suction-producing means connected with said return line and automatic means for controlling said suction producing means 85 to vary the degree of pressure in the return line inversely with the rise and fall of temperature in said return line.

23. In a heating system, the combination of a boiler and the supply and return lines 90 of a heat distributing system connected thereto, suction-producing means connected with said return line, means for controlling the boiler to change the pressure in the supply line and automatic means for substantially simultaneously controlling the suction-producing means to change the pressure in 95 the return line inversely to the change of pressure produced in the supply line.

In testimony whereof I have signed this 100 specification in the presence of two subscribing witnesses.
